UNITED STATES PATENT OFFICE.

ALBERT D. MORROW, OF CORDOVA, ALABAMA.

WIRE-STRETCHER.

1,256,353.

Specification of Letters Patent. Patented Feb. 12, 1918.

Application filed February 9, 1916. Serial No. 77,264.

To all whom it may concern:

Be it known that I, ALBERT D. MORROW, a citizen of the United States, residing at Cordova, in the county of Walker and State 5 of Alabama, have invented certain new and useful Improvements in Wire-Stretchers; and I do hereby declare the following to be a full, clear, and exact description of the invention, such as will enable others skilled 10 in the art to which it appertains to make and use the same.

The invention relates to improvements in wire stretchers.

The object of the present invention is to 15 improve the construction of wire stretchers and to provide a simple, practical and inexpensive wire stretcher of strong and durable construction, capable of enabling a plurality of fence wires to be simultaneously stretched 20 by one person, and of exerting the desired force on the wire to stretch the same to the proper tension.

A further object of the invention is to 25 provide a wire stretcher of this character equipped with a double ratchet mechanism for advancing the wire step by step to the desired point and provided with means for simultaneously disengaging both dogs or pawls from the ratchet bar to permit the 30 wire stretcher to be readily rearranged for another stretching operation without liability of the parts sticking and interfering with the readjustment of the device.

With these and other objects in view the 35 invention consists in the construction and novel combination and arrangement of parts hereinafter fully described, illustrated in the accompanying drawings and pointed out in the claim hereto appended, it being understood that various changes in the form, proportion and minor details of construction may be resorted to without departing from the spirit or sacrificing any of the advantages of the invention.

45 In the drawings—

Figure 1 is a plan view of a wire stretcher constructed in accordance with this invention, portions of the operating lever being broken away,

50 Fig. 2 is an edge view of the wire stretcher,

Fig. 3 is a transverse sectional view on the line 3—3 of Fig. 1,

Fig. 4 is a detail sectional view on the line 55 4—4 of Fig. 1,

Fig. 5 is a similar view on the line 5—5 of Fig. 1,

Fig. 6 is a detail view of the clamp for engaging the fence wires.

Like numerals of reference designate corresponding parts in the several figures of the drawings.

In the accompanying drawings in which is illustrated the preferred embodiment of the invention, the wire stretcher comprises 60 in its construction a longitudinally disposed ratchet bar 1, a transversely disposed operating lever 2 and a pair of converging angularly disposed pawls or dogs 4 pivoted at their outer ends at 5 and 6 to the operating lever at opposite sides of the ratchet bar and adapted to alternately engage the teeth thereof when the operating lever is oscillated.

The ratchet bar is provided at one end 75 with an opening 7 for the reception of an anchoring chain 8 which is secured around a post 9 toward which the wires 10 are to be stretched. The ratchet bar is also provided with a longitudinal slot 11 terminating short 80 of the ends of the ratchet bar and receiving a bolt 12 which constitutes a pivot for the operating lever and which also connects a pair of bars 13 with the lever. The lever is provided with a longitudinal opening 14 to 85 receive the ratchet bar, the opening being preferably formed by a separate bar or piece of material 15 secured to the operating lever at one side thereof as clearly illustrated in Fig. 3 of the drawings. A pivot bolt 12 90 operates in the slot 11 and is adapted to move along the same in the operation of the wire stretcher and the outer ends of the pawls or dogs are arranged in the opening 14 of the operating lever. The inner engaging 95 end of the pawls or dogs 4 are provided with teeth 16 and they have flanges 17 arranged in pairs and located at opposite sides of the teeth 16 and adapted to slidably embrace the side portions of the ratchet bar 1. 100

The pawls or dogs are maintained in engagement with the side edges of the ratchet bar by means of coiled springs 19 secured at 20 in the opening 14 of the operating lever and at their other ends at 21 to the pawls 105 or dogs at the inner side edges thereof adjacent to the jaws or engaging portions of the same. The coiled springs are arranged at an angle to the pawls or dogs 4 and are located at the inner sides of the same and 110

they yieldably maintain the said pawls or dogs in engagement with the ratchet bar which is provided at its side edges with ratchet teeth 22 shouldered at one end and 5 beveled at their side edges. The operating lever is adapted to be oscillated on the pivot 12 which will cause the pawls or dogs to engage the ratchet teeth alternately and advance the ratchet lever and the bars 13. 10 The bars 13 have offset portions 23 to embrace the operating lever and the said bars 13 extend through guides 24 of the ratchet bar and have their rear ends spaced apart by block 25 and equipped with a clevis 26 15 secured to the bars 13 by a bolt 27 which also pierces the ends of the bars 13 and the spacing block 25. The clevis is connected by a chain 28 with the clamp 29 composed of bars or members and connecting bolts 30 which 20 cause the bars or members of the clamp 29 to engage the wire to be stretched. The device is adapted for stretching a plurality of fence wires or woven wire fencing or the like and after the pulling or connecting 25 bars 13 have been moved forwardly to the limit of the operation of the device, the pawls or dogs are swung outwardly by releasing mechanism to permit the slidable bars 13 and the transverse operating lever 30 to be drawn outwardly to arrange the parts for another operation of the wire stretcher.

The releasing mechanism comprises a pair of levers 31 and 32 each having a pivot portion 33 and an inner arm 34, the pivot portion 35 being mounted in the operating lever at opposite sides of the opening 14 thereof and the said arms being arranged to swing in the opening 14 and engage the pawls or dogs at the inner side edges thereof for 40 swinging the said pawls or dogs outwardly against the action of the coiled springs. The lever 31 is provided with a rearwardly extending arm 35 and the other lever has a forwardly extending arm 36 connected with 45 the rearwardly extending arm 34 by a rod 37 and with a latch lever 38 by a rod 39. The operating lever 2 is provided with a grip or handle 40 and the latch lever is located at the grip or handle 40 in position to 50 be grasped simultaneously with the same.

The latch lever is fulcrumed at its inner portion to the operating lever and when it is pressed against the handle or grip thereof, the arms 34 of the said levers 31 and 32 are 55 swung outwardly and carry with them the

pawls or dogs which are moved out of engagement with the ratchet bar. The ratchet bar is thereby released and the lever with its central connecting means may be moved rearwardly for arranging the wire stretcher 60 for another operation.

It will be seen that the wire stretcher is exceedingly simple and inexpensive in construction, that it is adapted to be easily and rapidly operated and is capable of being 65 quickly reset for a second operation also it will be apparent that the pawls or dogs are adapted to be simultaneously disengaged from the ratchet bar and may be readily held out of such engagement while the parts 70 are being adjusted.

What is claimed is:—

A wire stretcher comprising a ratchet bar provided at opposite sides with ratchet teeth, an operating lever disposed transversely of the ratchet bar and slidably connected therewith, pawls located at opposite sides of the ratchet bar and pivoted at one end to the lever and having their other ends engaging the ratchet teeth, separate springs 75 located at opposite sides of the ratchet bar and connected with the pawls for urging the same into engagement with the said ratchet bar, and releasing mechanism comprising a pair of releasing levers carried by 80 the operating lever and located between and engaging the pawls at the inner sides thereof, one of the releasing levers being pivoted at one end and the other releasing lever being pivoted at a point intermediate of its 85 ends to provide an arm, a rod connecting the arm of such releasing lever with the other releasing lever and pivoted to the latter at a point intermediate of the ends of the same, and a latch lever mounted on the operating lever and connected with the said rod and adapted to move the releasing levers simultaneously in an outward direction, said 90 pawls operating independently of the operating mechanism in the ratchet action of the 95 wire stretcher and the said springs permitting the said pawls to swing outward independently of each other and also of the operating mechanism.

In testimony whereof I affix my signature 105 in presence of two witnesses.

ALBERT D. MORROW.
